PAGE 2

Fig. 2.

Des. 181,157

PAGE 3

Fig. 3.

Fig. 4.

Figure 1 is a perspective view of an electric food comminuting machine embodying my new design, viewing the same from the top, front and one side thereof;

Figure 2 is a perspective view of the electric food comminuting machine viewing the same from one side, substantially at eye level;

Figure 3 is a perspective view looking at the front of the electric food comminuting machine and viewed substantially at eye level; and

Figure 4 is a plan view thereof.

The dominant features of my design reside in those portions thereof shown in full lines.

I claim:

The ornamental design for an electric food comminuting machine, as shown and described.
